UNITED STATES PATENT OFFICE.

CHARLES E. WAKEMAN, OF PONTIAC, MICHIGAN, ASSIGNOR OF ONE-HALF
TO P. A. HITCHCOCK, OF SAME PLACE.

KNIT FABRIC AND STOCKING.

SPECIFICATION forming part of Reissued Letters Patent No. 9,550, dated February 1, 1881.

Original No. 174,339, dated February 29, 1876; Reissue No. 8,353, dated July 30, 1878. Application for reissue filed November 23, 1880.

To all whom it may concern:

Be it known that I, CHAS. E. WAKEMAN, of Pontiac, in the county of Oakland and State of Michigan, have invented certain new and useful Improvements in Knit Fabrics and Stockings; and I do hereby declare that the following is a full, clear, and exact description thereof, reference being had to the accompanying drawings, and to the letters of reference 10 marked thereon, which form a part of this specification.

My invention consists in a fulled knit woolen fabric provided with a lining of woolen loops designed to be used as will be hereinafter more 15 fully set forth.

In order to enable others skilled in the art to which my invention appertains to make and use the same, I will now proceed to describe its construction and operation, referring to the 20 annexed drawings, in which—

Figure 1 is a side view of a stocking embodying my invention. Fig. 2 shows a piece of the goods.

To illustrate an article made in accordance 25 with my invention, A represents a woolen sock made on an ordinary knitting-machine in the usual manner. This stocking is then placed in an ordinary fulling-machine and there manipulated in the manner usual to such machines, whereby the same is fulled and thickened, forming a nap on the outside and inside 30 thereof. While still wet from the fulling the

sock is drawn upon a flat pattern-board having the general outline of the human leg and foot and left to dry upon such pattern-board, 35 so that the dry fulled sock will be shaped to conform to the general contour of the foot and leg. After the stocking has been fulled and shaped it is lined throughout by means of a series of circumferential rows of woolen 40 loops, B, sewed in by hand or otherwise, as shown, forming a soft, yielding, and pliable lining.

Socks thus made may be used without shoes by attaching a sole of buckskin or other suitable material to the under side of the foot. 45

Having thus fully described my invention, what I claim as new, and desire to secure by Letters Patent, is—

1. As a new article of manufacture, a fulled 50 knit fabric provided with a lining of woolen loops, constructed substantially for the purpose and in the manner herein described.

2. As a new article of manufacture, a fulled knit stocking provided with a seamless leg 55 and a seamless foot with a lining of woolen loops, and shaped to correspond with the general contour of the foot and leg, substantially as described.

CHARLES E. WAKEMAN.
